UNITED STATES PATENT OFFICE.

FRANK WARNER BRANDOW, OF PITTSFIELD, MASSACHUSETTS, ASSIGNOR TO JACOBSON-BRANDOW COMPANY, OF PITTSFIELD, MASSACHUSETTS, A CORPORATION OF MASSACHUSETTS.

SPARK-INDICATOR.

No. 926,976.

Specification of Letters Patent.

Patented July 6, 1909.

Application filed August 5, 1907. Serial No. 387,056.

To all whom it may concern:

Be it known that I, FRANK WARNER BRANDOW, a citizen of the United States, residing at Pittsfield, in the county of Berkshire and State of Massachusetts, have invented certain new and useful Improvements in Electric-Circuit Devices to be Designated as a Spark-Indicator, of which the following is a specification.

10 This invention relates to devices adapted to form part of an electric circuit, employed to ignite a combustible charge operating a motor engine, and to determine the operative condition of such circuit.

15 One object of my invention is to provide a comparatively simple and inexpensive device adapted to form part of an electric circuit for the purpose described which may be easily attached to or detached therefrom and 20 which shall visibly indicate the strength and frequency of sparks emitted by the current within the engine and the operative efficiency of the several parts forming the completed circuit without necessitating their removal.

25 And a further object is to enable the operator to thereby readily retime the ignition, when that is necessary, without removing any part of the engine, and with these and other objects in view my invention consists in certain 30 features of construction and arrangement of parts as hereinafter described and claimed, reference being had to the drawings, forming a part of this specification, in which corresponding parts are designated by similar reference characters in each of the views.

Referring to the drawings, Figure 1 is a perspective side view illustrating a preferred form of my device operatively attached to parts of an electric circuit of the character described; Fig. 2, a vertical longitudinal section of my device on an enlarged scale; Fig. 3, a detailed bottom view of the base; Fig. 4, an end view of the casing, B⁴, with the flange thereon; the inclosed stem being shown in cross-section; Fig. 5, a sectional view of my device attached to a spark-plug of modified construction; Fig. 6, a side view of a section of my device, showing a modified construction of the sliding stem, B³; Figs. 3, 4 and 6 also being on an enlarged scale.

Referring to the drawings by letters and

numerals, B represents a base of fiber, or other suitable insulation, provided at either end thereof with metallic conductors forming parts of an electric circuit and respectively 55 adapted to be readily attached to or detached from the same, and further adapted to be electrically connected or disconnected relatively to each other.

B³ is a stud rigidly mounted upon one end 60 of the base and constructed to support in stationary position over the same and parallel thereto a cylindrical casing or tube, B⁴. Said casing is adapted to support a sliding stem, B³, having free longitudinal and rotary movements therein, and a co-operative helical spring, B⁹. Said stem is provided at its outwardly directed end with a manipulative button or retractor, B⁶, of fiber or other suitable insulation, and at its inwardly 65 directed end with an enlarged preferably conical spark point, B¹², constructed to move frictionally within the said casing and to protrude from its inwardly directed end, and with a plurality of stop pins, B⁷, spaced relatively apart at predetermined points centrally of the stem, approximate the other end of the casing and within the same.

B¹³ represents an inwardly projected flange of the casing provided with a notch, B¹⁴, 80 therein in the line of movement of the stop pins, B⁷, of sufficient size to allow their passage therethrough.

B¹⁵ denotes a metallic plate held in position against the underside of the base by the riveted end, B⁸, of the stud and preferably provided laterally with side-clips or clamping arms, B¹⁸, and a depending perforated terminal, B¹⁶, separately provided with like clips or arms. Said clamping-arms, B¹⁸, are adapted to hold in position a cable, C, containing a feed-wire, C', secured to the terminal; B¹⁶, by the clamping-arms respectively provided thereon. B⁷ represents a clamp rigidly secured to the top of the opposite end of the 95 base preferably by means of a hollow rivet, B¹⁷, passed transversely through said parts and an intermediate metallic plate, B²⁰, similar to plate B¹⁵, said rivet being provided with a socket or recess, B¹¹, in the bottom 100 thereof. Said clamp is preferably constructed of a resilient metallic strip having

its clamping end bent double, so as to bear movably against the underside of the base, and provided with an open slot, B¹⁰, adapted to receive and hold in engagement with the 5 socket B¹¹ the head, A¹, of a spark-plug, A, constructed as shown in Fig. 1. Said clamp is further provided with a free end raised substantially perpendicular to the base so as to form a terminal, B², in contact with the 10 spark point B¹².

In Fig. 6 a modified construction of an adjustable electrode is illustrated in which the sliding-stem, B³, is provided with a screw thread in substitution for stop-pins, B⁷, 15 while the flange on the casing, B⁴, is accordingly provided with a screw threaded edge to engage therewith.

It may readily be seen that other approved forms of spark-plugs may be adopted for use 20 in connection with my device in preference to the particular construction heretofore described. An illustration of such other form is shown in Fig. 5. In this instance a head, A¹, is provided with a screw-threaded stem, 25 A³, projected through the slotted clamp, B¹, the hollow rivet, B¹⁷, and intermediate parts, while a knurl-nut, A², engaging with the stem, A³, secures the parts firmly together in electrical connection.

30 The operation of my device may be described as follows: When forming a part of a completed circuit my device is adjusted substantially as hereinbefore described and as indicated in Fig. 1 wherein the spark point, B¹², is forced outwardly by means of the helical spring, B⁹, in frictional contact with the terminal, B², thus offering an easy path for the passage of the current. When, however, the operator desires to determine the 40 operative condition of the circuit the point, B¹², is retracted by means of the manipulative button, B⁶, so as to cause a spark space, B¹⁶, as shown in Fig. 2. When sufficiently retracted to give the desired amount of space 45 the said button is rotated slightly to one side so that the stop-pin, B⁷, last withdrawn through the notch, B¹⁴, provided in the flange on the casing, B⁴, as described, bears against the flange when the button is released, thus 50 preventing the closing of the circuit. As a result of this operation the current is forced to arc over the space, B¹⁶, producing in its passage a visible spark in synchronism with the ignition spark emitted by the spark-plug 55 within the engine. This result proves the operative condition of the circuit without requiring the removal of any part thereof. If, however, the electrical energy be nil or so feeble as to be unable to force a passage the 60 defective condition of the circuit is at once observed by a weak or intermittent spark or by the entire absence thereof. When employed on a multi-cylinder motor my device will enable the operator to locate instantly 65 and without the removal of any part the

particular circuit in defect and whether such defect be in the general circuit system or in a particular cylinder. Furthermore, the operator is enabled by these means to accurately retime the ignition within the engine. 70

Having fully described my invention I claim as new and desire to secure by Letters Patent:—

1. In a spark indicator, the combination with an insulation base, of a stationary electrode and an adjustable electrode oppositely mounted on the base, said adjustable electrode comprising an upwardly extending support, a sleeve or casing on said support, a movable stem-member projected through the sleeve, and means for keeping the stem-member normally in contact with the stationary electrode. 75

2. In a spark indicator, the combination with an insulation base, of an adjustable electrode mounted on the base and comprising an upwardly extending support, a sleeve or casing on said support, a movable stem-member projected through the sleeve and provided at one end with a contact-point and 80 at the other end with means for manipulating the stem-member. 90

3. In a spark indicator, the combination with an insulation base, of oppositely disposed electrodes mounted thereon, one of said electrodes comprising an upwardly extending support, a sleeve or casing on said support, a rotatable stem-member projected through the sleeve and adapted to be normally in contact with the other of said electrodes, and means for holding said rotatable member in a retracted position. 95

4. In a spark indicator, an adjustable electrode comprising a sleeve or casing provided at one end with an interior annular flange or edge having a notch therein, a slideable stem for projection through the sleeve, a plurality of spaced pins or stops provided laterally on the stem within the sleeve and adapted to pass through the notch in said 100 flange, and means for retracting and rotating the stem within the sleeve. 105

5. In a spark indicator, the combination with an insulation base, of oppositely disposed electrodes mounted on the base, one of said electrodes comprising an upwardly extending support, a sleeve or casing on said support, a slideable stem-member projected through the sleeve, spring means within the sleeve tending to keep said stem-member 110 normally in contact with the other of said electrodes, and insulating means provided on said stem-member for manipulating the same. 115

6. In a spark indicator, the combination with an insulation base, of a stationary electrode and an adjustable electrode oppositely mounted on said base, said base and stationary electrode having means for attachment and connection to a spark plug and said ad- 120 125 130

justable electrode having a metal standard carrying a metal casing or sleeve, a movable metal stem member projecting through the casing and means for keeping the stem member normally in contact with the stationary electrode, and means for making electrical connection to the standard.

In testimony whereof I have affixed my signature, in presence of two witnesses, this thirty-first day of July, A. D. 1907.

FRANK WARNER BRANDOW.
